BUFFING WHEEL

Fritz E. Hendrickson, South Elgin, Ill., assignor
of one-half to Murray Ireland, near Elgin, Ill.

Application March 24, 1941, Serial No. 384,849

6 Claims. (Cl. 51—193)

My invention relates to buffing wheels and particularly to buffing wheels of the so-called "hard" type.

An object of my invention is to provide a novel form of a hard buffing wheel comprising a minimum number of integral parts.

Another object of my invention is to provide a new and improved form of buffing wheel section comprising a plurality of cloth disks having simple means for supporting and driving the same.

Another object of my invention is to provide a novel form of a section for a hard buffing wheel adapted to be supported and driven by means causing no compression of the operative area of the section.

Other objects of my invention will either be apparent from a description of one form of section and supporting and driving means therefor embodying my invention or will be pointed out in the course of such description and set forth in the appended claims.

In the drawings—

Figure 1 is a fragmentary view, in front elevation, of a buffing wheel embodying my invention,

Fig. 2 is a fragmentary view corresponding substantially to that shown in Fig. 1 but taken on the line 2—2 of Fig. 1,

Fig. 3 is a view in front elevation of a supporting and driving disk embodying my invention,

Fig. 4 is a view, in side elevation, of the element shown in Fig. 3, and,

Fig. 5 is a fragmentary front elevational view of one section of flexible disks embodying my invention.

My improved buffing wheel includes at least one section comprising a plurality of annular disks of cloth, all disks having the same outer diameter but certain disks having a given inner diameter and other disks having a smaller or lesser inner diameter. Referring, for instance, to Fig. 2 of the drawings, I have there shown a plurality of such sets of flexible disks, all having the same outer diameter. A predetermined number of disks or plies 11 of substantially annular shape have a given inner diameter. Each set includes a plurality of disks 13 of the same material as the disks 11 and of the same external diameter but of a lesser inner diameter. For illustrative purposes I may mention that I may employ from 8 to 12 disks of flexible cloth in each of the two sets 11 and 13 although it is to be understood that this is mentioned merely to give an idea of the approximate axial thickness of the two sets of plies or disks of cloth.

I prefer to use a plurality of circular or spiral

seams 15 to sew together the cloth disks in the two sets of each section, as will be noted from Fig. 2 of the drawings.

The disks of lesser internal diameter are provided with a plurality of relatively wide openings or apertures 17 these apertures being usually uniformly peripherally spaced around the area of the disks 13 just outside of the inner periphery thereof. I provide further a plurality of seams 19 immediately outside of the inner periphery of the disks 13 in order to strengthen the sets of disks immediately adjacent the inner periphery thereof.

A driving and supporting means for the sections is shown in Figs. 3 and 4 of the drawings and includes a disk 21 which may be of any suitable material, such as metal, and when made of relatively strong metal I find it possible to make the thickness of the disk 21 relatively small. I provide a plurality of initially radially extending projections 23 of relatively appreciable peripheral width. The alternate projections 23 are then return-bent, substantially as shown in Figs. 2 and 4 of the drawings. In the assembly of an operative buffing wheel, a disk 21 may be laid upon a horizontal surface such as a table or a bench and two sections of the cloth disks are first placed in back-to-back relation, as shown particularly in Fig. 2 of the drawings. The length, in a radial direction, of the return-bent projections 23 is made such that I find it possible to locate the alternate projections on a disk 21 in the cooperating openings 17 in the two sets of cloth disks of lesser internal diameter. Proper cooperative dimensions of the radial diameter of the apertures 17 and the proper amount of bending or, in general, the shape of the hook portion constituted by the return-bent projection 23, permits of easily and quickly mounting a pair of sections located in back-to-back positions on one set of hooks 23.

The disk 21 may then be turned over and a second pair of sections may be operatively engaged with the other or alternate hook members 23, as shown in Fig. 2 of the drawings.

A buffing wheel of this kind is, of course, usually supported on a driving shaft 25 and I may locate washers 27 between each adjacent pair of driving members 21, the axial thickness of the washers 27 being just sufficient to ensure that the respective sections of cloth disks shall be positioned closely adjacent to and in engagement with each other. While I have shown only two supporting members 21 in Fig. 2 of the drawings, I desire it to be understood that I may assemble a buffing wheel of any desired axial length by the

use of any desired number of supporting and driving means 21, each having hook or return-bent portions interengaging with apertures in a part only of the cloth disks driven by the respective driving members.

I have found that a buffing wheel of this kind in which careful attention has been given to the number of seams in the sections is an effective buffing wheel of the so-called "hard" type, particularly useful on soft materials such as aluminum. I desire to point out that by the selection of the thickness of the spacing washers 27 in co-operation with the number of disks in each of the sets and sections, my invention provides a hard buffing wheel in which no compressive stress is applied to that portion of the disks which are used for actual buffing operation, which has so often been the case in structures of this kind in which annular disks of cloth were clamped between metal flanges extending outwardly beyond the inner diameter of the disks and interengaged therewith as by axially extending bolts passing through the flanges and through the cloth disks adjacent to and outside of the inner periphery of the latter.

Various modifications may be made in the device embodying my invention as herein shown and described and all such modifications clearly coming within the scope of the appended claims are to be considered as being covered thereby.

I claim as my invention:

1. A hard buffing wheel having a section comprising a plurality of annular disks of cloth all having the same outer diameter, certain of said disks having a lesser inner diameter than the other disks, seams holding all of said disks close together and extending to the larger inner diameter, seams holding together all of the disks of lesser inner diameter adjacent to said lesser inner diameter and a plurality of peripherally spaced openings in said disks of lesser inner diameter within the inner diameter of the other disks adapted to receive a supporting and driving means.

2. A hard buffing wheel comprising a first set of circular cloth disks of a given outer diameter and a given inner diameter, a second set of circular cloth disks of the same outer diameter as the first set and of a smaller inner diameter than the first set, a plurality of seams securing both sets together over substantially the entire area of said first set, a seam securing together said second set adjacent to their inner periphery, and a plurality of peripherally spaced openings in said second set of disks adjacent to their inner diameter and within the inner periphery of said first set of disks for receiving a supporting and driving means.

3. A hard buffing wheel having a section comprising a first set of circular fabric disks of a given outer diameter and a given inner diameter, a second set of circular fabric disks of the same outer diameter and of a smaller inner diameter, a plurality of seams distributed substantially uniformly of the area of the disks of said first set

to hold both sets tightly together, a second pair of like sets of fabric disks in back-to-back position relatively to said first pair, and a plurality of openings in each of the second set of disks of each pair for receiving a supporting and driving means.

4. A hard buffing wheel having a section comprising a first set of circular fabric disks of a given outer diameter and a given inner diameter, 10 a second set of circular fabric disks of the same outer diameter and of a smaller inner diameter, a plurality of seams distributed substantially uniformly of the area of the disks of said first set to hold both sets tightly together, a second pair of like sets of fabric disks in back-to-back position relatively to said first pair, a plurality of peripherally spaced apertures in each of said second sets of disks adjacent to the inner periphery of said second set and inside of the inner periphery of said first set and a holding and driving means for said body interengaged with said apertures and free of compression stresses on said fabric disks.

5. A hard buffing wheel having a section comprising a first set of circular fabric disks of a given outer diameter and a given inner diameter, 25 a second set of circular fabric disks of the same outer diameter and of a smaller inner diameter, a plurality of seams distributed substantially uniformly of the area of the disks of said first set to hold both sets tightly together, a second pair of like sets of fabric disks in back-to-back position relatively to said first pair, a plurality of peripherally spaced apertures in each of said second sets of disks adjacent to the inner periphery of said second set and inside of the inner periphery of said first set and a holding and driving means for said body comprising a disk having a plurality of hook portions at its outer periphery of said disk and bent flat-wise into hook shape, alternate 30 hooks interengaging with the apertures in said sets of smaller inner diameter to hold and drive the same free of compressive stress on said fabric disks.

6. A hard buffing wheel comprising a plurality 45 of sections each including a first set of adjacent imperforate circular fabric disks of a given outer diameter and of a given inner diameter, a second set of adjacent circular fabric disks of the same outer diameter and of smaller inner diameter, a plurality of seams extending through the disks of both sets over the area of the disks of larger inner diameter to hold the fabric disks of both sets tightly together, a plurality of openings in said second sets of disks of smaller inner diameter adjacent to their inner diameter and inside of the inner periphery of said first set of fabric disks, at 50 least one seam in each second set of disks between said openings and the inner diameter of said disks, a driving and supporting disk having a plurality of return-bent hook portions at its outer periphery, alternate hook portions being bent toward opposite sides of said driving disk and interengaged with the openings in two sections.
